Albert D. Grover

by *John D. Grover*
Atty.

UNITED STATES PATENT OFFICE.

ALBERT D. GROVER, OF NEW YORK, N. Y.

BRIDGE FOR MUSICAL STRINGED INSTRUMENTS.

Application filed November 20, 1919. Serial No. 339,403.

To all whom it may concern:

Be it known that I, ALBERT D. GROVER, a citizen of the United States of America, residing at New York city, in the county 5 and State of New York, have invented certain new and useful Improvements in Bridges for Musical Stringed Instruments, of which the following is a specification.

My invention relates to certain improvements in bridges for stringed musical instruments, such as violins and banjos.

The primary object of the invention is to provide means for securely retaining the bridge of a stringed musical instrument in position under the taut strings of the instrument, and I accomplish this object by the provision of a transverse supporting member having releasable locking engagement with the bridge proper.

Another object of the invention is to provide a construction whereby a supporting member of any given size is usable with equal facility with bridges of different designs and dimensions. Other objects of the invention will be apparent from the subjoined description.

It is not broadly new to provide a transverse supporting member for the bridge of a musical instrument, this construction being disclosed and claimed in United States Patent No. 769,649, issued to me on the 6th day of September 1904. The present invention is a development of that forming the subject matter of said patent, and differs therefrom in that I now provide a locking interengagement between the bridge and its transverse support, as distinguished from a mere frictional engagement between these parts as in the earlier construction.

Several forms of the invention are illustrated in the accompanying drawing, wherein Fig. 1 is a perspective view of a bridge and its transverse support in interengagement; Figs. 2, 3 and 4 are side elevational views of bridges differing slightly from each other in construction; Fig. 5 is a side elevational view of the transverse supporting member; Fig. 6 is an inverted plan view of Fig. 2; Fig. 7 is a cross sectional view on the line 7—7 of Fig. 2; Fig. 8 is a perspective view of a somewhat modified form of bridge in connection with which these transverse supports are employed; Fig. 9 is a perspective view of one of the supports of Fig. 8, differing only from the support of Fig. 5 in being heavier in construction; and Fig. 10

is an enlarged perspective view of one end of the bridge of Fig. 8, the transverse support being omitted.

Referring first to Figs. 1 to 4, it will be noted that the bridge comprises the string receiving bar 10 and the supporting legs 11, the upper edges of each bar 10 being provided with notches 12 for the reception of the strings of the instrument. The notches 12 differ in number and arrangement, according to the string arrangement of the instrument for which the bridge is designed to be used. Each bar 10 is substantially wedge shaped tapering from a relatively broad base 13 to a relatively narrow apex 14. The thickness of the bars 10 differs in the several forms of Figs. 1 to 4, the bar of Fig. 1 being the thickest or widest, and that of Fig. 4 being thinnest or narrowest, it being understood that different instruments require different grades of bridges.

Provided in the opposite faces of each bar 10, extending upwardly from base 13, are elongated slots 15 laterally delimited or defined by the parallel projecting walls 16. In the form of Figs. 1 to 3 there is provided below the lower ends of the slots 15 a notch 17, the purpose of which will be later described. In Fig. 4 the notch is dispensed with, the slots 15 extending down to the base 13.

The transverse supporting member, shown in Fig. 5, comprises an arched yoke 18 having a parallel-walled slot 19 cut in its highest part, and legs 20 at opposite ends of the yoke. The slot 19 extends in a direction at right angles to the longitudinal axis of the yoke 18. The supporting member constitutes, in effect, a supplemental bridge taking strains in a direction at right angles to those taken by the main bridge.

The lower faces of the legs 11 and 20 may be provided with a thin layer 21 of a non-slipping substance, such as very finely comminuted carborundum.

The bridge and transverse support are assembled, for use, as shown in Fig. 1, with the walls of slot 19 spanning the intact portion of the bar 10 between the slots 15, and the walls 16 interlocking with the walls which delimited the slot 19. It will be noted that the bridge and transverse support extend at right angles to each other and owing to the interengagement or interlocking of the walls, as stated, the parts remain firmly secured together and are assured against tip-

ping even under the maximum strains of the strings on the bar 10.

As will be seen in Figs. 2, 3 and 4, the main bridges are of different widths and designs adapted to the different instruments for which they are used.

In Fig. 2 the bridge is heavy and is provided with eight notches 12 to support and space the eight strings of the so-called mandolin banjo. In this design the notches 17 are cut deeper than in the light bridge having four notches 12 owing to the lightness of the bridge as shown in Fig. 3. In Fig. 4 the notch 17 is not necessary. The object of the notches 17 is to make the distance between lines A and B the same in all designs of bridges. This is done so that only one size of transverse support having a slot 19 of uniform depth is necessary for all kinds of bridges. In the manufacture of wooden bridges it is impossible to make the widths of the string supporting bars exactly the same, so that even in one design of bridge these bars may vary from .001" to .010". It is absolutely necessary that the feet of the main bridge and the transverse support be perfectly level, all touching the head or vellum of the instrument uniformly. In the process of manufacturing the bridge maple blocks are passed over a circular saw of the depth of the notch 17. This saw projects above the saw table the exact distance as shown between lines A and B thus allowing the same transverse support to be used. This support is made of fibre and punched out with dies. They will all be of exact size to .001".

If different supports were necessary many different sets of dies would have to be used, thus causing great expense and confusion.

It will be understood that while the feature of making a single transverse support available for use with a variety of bridges forms an important part of my invention, it is nevertheless within the purview of the invention to provide a separate support for each kind of bridge.

In the form of bridge shown in Figs. 8 and 10, the bar 10^a is not provided with integral legs as in the other forms, but has adjacent each of its ends the slots 15^a and an undercut notch 17^a, thus being adapted to receive at each end a transverse support of the weight and construction shown in Fig. 9. The support of Fig. 9 is identical in construction with that shown in Fig. 5 and the same reference characters are applied to the parts thereof. It will of course, be apparent that the notches 17^a may also be omitted from this form of the invention, although such construction would be less desirable.

I claim:—

1. The combination with the bridge of a

stringed musical instrument, of a transverse support therefor, and parallel walls disposed longitudinally in the bridge and transversely in the support for fixing their relative positions and releasably interlocking said parts.

2. The combination with the bridge of a stringed musical instrument, the bar of said bridge having oppositely disposed slots therein, of a transverse support having a slot the walls of which are parallel with each other and with those of the bridge and designed to enter and interlock with the walls of the slots of the bar.

3. The combination with the bridge of a stringed musical instrument, the bar of said bridge having oppositely disposed parallel slots and a notch at one end of said slots, of a transverse support having a slot the walls of which are parallel with each other and with those of said bridge and designed to enter the slots of the bar and a portion of the support below the slot therein being adapted to enter said notch, whereby the relative positions of the two parts remain fixed.

4. The combination with the bridge of a stringed musical instrument, the bar of said bridge having slots parallel to each other in its opposite faces, of a transverse support for said bridge having a slot the walls of which are parallel with each other and with those of said bridge and designed to enter and interlock with the walls of the slots of said bar to fix the relative positions of the two members.

5. The combination with the bridge of a stringed musical instrument comprising a tapered bar having slots provided with opposite parallel walls extending upwardly from the base of the bar, of a transverse support for the bridge having a parallel-walled slot the walls whereof are designed to enter and interlock with the walls of the slots in said bar to fix the latter against lateral displacement.

6. A bridge for a musical stringed instrument comprising a tapered bar having near each end slots in opposite faces thereof, all of the walls of said slots being parallel to each other and a notch at the end of each pair of slots, and a transverse support for each end of the bar, each of said transverse supports having a parallel-walled slot the walls whereof are adapted to enter a pair of slots in the bar and an intact portion of which is designed to enter a notch, whereby relative adjustment of the two members may be limited to vertical movements.

In testimony whereof I have affixed my signature in presence of two witnesses.

ALBERT D. GROVER.
